UNITED STATES PATENT OFFICE.

MARTIN E. OHRNSTEDT, OF ALLENTOWN, PENNSYLVANIA.

GAS OR GASOLENE BURNER.

SPECIFICATION forming part of Letters Patent No. 740,307, dated September 29, 1903.

Application filed October 17, 1902. Serial No. 127,716. (No model.)

To all whom it may concern:

Be it known that I, MARTIN E. OHRNSTEDT, a citizen of the United States, residing at Allentown, in the county of Lehigh and State 5 of Pennsylvania, have invented new and useful Improvements in Gas or Gasolene Burners, of which the following is a specification.

This invention relates to gas and gasoline burners adapted for general heating purposes, 10 but particularly applicable to gas and gasoline stoves and the like; and the primary object of the same is to provide a simple and effective burner which is so constructed that the weight of the article or device to be heated placed 15 thereon will open a valve to admit gas to the burner and one wherein the removal of the weight of the article or device being heated from the burner will cause the valve to be closed, thereby economically using the gas.

20 A further object of the invention is to provide in an automatic burner of the character set forth a supplemental burner or pilot which remains continuously ignited to serve as a means for lighting the main burner when the 25 gas is admitted to the latter without unnecessarily wasting the gas when the apparatus is not in actual heating use or when one article is removed therefrom before another is placed thereon, and also by this means relighting of 30 the apparatus is avoided.

With these and other objects and advantages in view the invention consists in the construction and arrangement of the several parts, which will be more fully hereinafter described and claimed.

35 In the drawings, Figure 1 is a vertical longitudinal section of the improved burner, showing the valve closed. Fig. 2 is a similar view showing the valve open and in condition to admit gas to the burner-chamber.

Similar numerals of reference are employed to indicate corresponding parts in the views.

1 designates a gas or gasoline supply or feed pipe which extends from a suitable gas- 45 supply source and is connected to the burner-body 2, having the mixing-chamber 3. The burner proper comprises a top or body section 4, let down into the mixing-chamber 3 and provided with a convex lower surface, as 50 clearly shown in the drawings. The burner also comprises an annular shell-rim 5, of arc-

uate form, provided with a plurality of outlet-openings 6. The body-section 4 is secured to the main body of the burner at intervals by screws or other like devices 7, passing vertically through the rim and interlocking flanges of the body-section and the upper portion of the main body of the burner, the outer edges of the rim 5 resting upon the upper edge of the burner-body. The body 2 is open at its upper end for convenience in the assemblage of the body-section 4 of the burner and an accurate disposition of the rim 5 on the upper edge of the burner-body. The section 4 is of such dimensions as to form a gas- 60 passage or annular duct 8 between the same and the adjacent wall of the burner-body 2 and also to leave the lower portion of the chamber 3 free to receive the gas or gasoline. The passage or duct 8 opens directly into the annular 65 space or supplemental chamber 9, formed by the arcuate rim 5, through which the gas has an un retarded flow, causing it to exit equally through all the openings 6. The section 4 is provided with an opening 10, extending vertically therethrough and adapted to admit of the vertical movement of a vertical post 11, carrying at its upper end a rest 12, which receives the weight of cooking utensils or other articles placed upon the burner. The lower 70 portion of the post 10 is tapered or gradually reduced to form a conical shoulder 13 and is then extended in the form of a stem 14, which passes through an opening in the bottom of the burner-body, the stem 14 having a disk 75 or plate 15 at its lower end, which rests upon and is upheld by a coiled spring 16, mounted in a box or cage 17, extending downward from and attached to the burner-body, a spring-seat 18 in the form of a plate or cross- 80 bar being arranged at the bottom of the box or cage to sustain the spring 16. The spring 16 normally upholds the stem 14 and rest 12 in the position illustrated in Fig. 1. Air-in- 85 let ports 18' are formed at suitable points in the burner-body, leading into the mixing-chamber for supplying the requisite amount of air.

Above the burner a suitable grate or grid 19 is disposed and held by means well known in the art in fixed position relatively to the parts below, so that articles or vessels placed

upon the rest 12 will be supported by the grid when the post and stem are depressed, and thereby relieve the latter devices of the direct weight after they have performed their functions. The grid has an opening at the center sufficiently large to permit the rest 14 to freely move up and down.

The pipe 1 communicates with the bottom of the mixing-chamber 3 to one side of the plane of movement of the stem 14, the gas or gasoline passing through a relatively small port 20, the upper end of which is adapted to be closed by a ball or gravitating valve 21 of such size and weight as to always seek its normal position when free to do so. This valve is normally disposed over the port 20 and shuts off communication between the chamber 3 and the pipe 1. As soon, however, as the stem 14 is depressed by the weight imposed upon the rest 12 the tapered portion of the post strikes or comes in contact with the valve and pushes it to one side, as shown in Fig. 2, thereby opening the port 20 and establishing communication between the pipe 1 and the chamber 3, permitting the gas to enter the latter and supply the burner. As soon as the weight is removed from the rest 12 the stem 14 assumes the normal position (shown in Fig. 1) and the valve immediately closes. The improved device is also supplied with an auxiliary or pilot burner which remains ignited continuously during the period that the burner is in use, and for this purpose I employ a branch supply-pipe 22, which enters the burner-body above the main supply-pipe 1, where it delivers gas or gasoline to a small nipple 23, arranged at one side of and in close proximity to the shell 5. The flow of gas through the branch pipe 22 may be entirely cut off by means of a shut-off cock or valve 24. When said cock or valve is opened, the gas passes through the pipe 22 and ignites at the nipple 23. When it is desired to prepare the improved burner for use, the valve or shut-off cock 24 is opened to allow the gas to flow through the pipe 22 to the nipple or tip 23, where it is ignited. It will be observed that the main burner will be unaffected by this supplemental or pilot burner until the valve 21 is opened in the manner above explained, whereupon the main burner will become ignited and so remain until the flow of gas is shut off from the main pipe or conduit 1. As soon as the valve 21 closes the main burner will become extinguished, and when again opened by the weight of the receptacle on the rest 12, as shown in Fig. 2, ignition will immediately take place, and so on through the full operation of placing an article or vessel upon and removing it from said rest. In this way an economical use

of gas will result and convenience in the mode of igniting the main burner will be afforded.

Having thus described the invention, what is claimed as new is—

1. In a device of the class set forth, the combination of a chamber with a concave bottom and having a burner disposed in the top thereof, the chamber being provided with a supply-conduit communicating with the bottom, a gravitating valve loosely mounted on the concave bottom and adapted to open and close communication between the supply-conduit and the chamber, and a vertically-arranged spring-actuated device movable through the center of the chamber and having a portion adapted to contact with the said valve, the vertically-movable device being depressed by the weight of an article placed thereon to automatically open the valve.

2. A device of the class set forth having a chamber with a concave bottom, a valve loosely mounted on said bottom to control the supply of gas to the chamber, and a device vertically movable through the chamber and having a portion adapted to contact with said valve and permit gas to enter the burner.

3. A device of the class set forth, comprising a chamber with an upper burner, a rim having openings therethrough, and a concave bottom, a gravitating valve controlling the supply of gas to the burner and freely movable over said bottom, a vertically-movable post extending through the center of the chamber and controlled by the weight of an article placed thereon to open the valve, and a supplemental burner close to said rim and which remains continuously ignited during the use of the entire device.

4. A device of the class set forth, comprising a burner-body having a mixing-chamber with a concave bottom, a main supply-pipe leading to a point to one side of the center of said bottom, a rolling valve normally closing communication between the supply-pipe and mixing-chamber, a movable post adapted by contact to unseat said valve and extending centrally through the said chamber, a rest connected with said post and adapted to be operated by an article placed over the burner, a branch pipe leading from the main supply-pipe to the burner-body, a burner-tip in communication with the branch pipe, and a shut-off cock controlling the branch pipe.

In testimony whereof I affix my signature in presence of two witnesses.

MARTIN E. OHRNSTEDT.
